(57) **CLAIM**

What is claimed is the ornamental design for the ice maker, as shown and described.

DESCRIPTION

FIG. 1 is a front perspective view of an ice maker in a configuration in which a door of the ice maker is closed; FIG. 2 is a front view thereof;

FIG. 3 is a right side view thereof;

FIG. 4 is a top view thereof;

FIG. 5 is a left side view thereof; and,

FIG. 6 is a left side view of the ice maker in an alternative configuration in which a door of the ice maker is open.

The rear and bottom of the ice maker form no part of the claimed design.

Elements shown in broken line form no part of the claimed design.
